ADJUSTABLE TONE VOLUME CONTROL
DEVICE FOR CHIME SIGNALS

John H. Wheclock, Fitzwilliam, N. H., and Frank Scherma, New York, N. Y., assignors to Signal Engineering & Manufacturing Company, New York, N. Y., a corporation of Massachusetts

Application November 24, 1937, Serial No. 176,308

5 Claims. (Cl. 177—7)

The present invention relates to audible signals of the type wherein a plunger is caused to strike a resonant metallic member, or chime bar. According to the present invention, there is provided improved means for adjustably controlling the volume of the sound given off when the resonant member is struck, so that only a pure tone will be heard, having the desired characteristics, as to loudness or softness.

10 The above and other advantageous features of the invention will hereinafter more fully appear from the following description, considered in connection with the accompanying drawing, in which:

15 Fig. 1 is a view in front elevation of a chime signal provided with an adjustable tone control device embodying the invention.

Fig. 2 is a view, partially in side elevation and partially in section, of the device of Fig. 1.

20 Fig. 3 is a fragmentary sectional view along the line 3—3 of Fig. 1, illustrating the adjusting device on an enlarged scale.

Fig. 4 is a plan view of the parts of Fig. 3.

Referring to the drawing, the signal consists 25 of a frame 1 partially of magnetic material, providing rods 2 for supporting a chime bar 3 above the top of the frame 1. The bar 3 is supported by cords 4 extending between the rods 2, with felt washers 5 provided at the points of support, 30 so that the bar 3 is entirely out of metallic contact with the rods 2 and frame 1. A hollow resonator 6 is mounted on the rods 2 above the bar 3.

The frame 1 provides a recess 1a, in which is 35 received a solenoid 7, and a plunger 8 of magnetic material is movable within an insulating tube 9, extending centrally through the solenoid 7. With the solenoid 7 in deenergized condition, the plunger 8 rests at the bottom of the tube 9. 40 with its upper end partially within the solenoid, so that when the solenoid 7 is energized, the plunger 8 is drawn upwardly within the solenoid with its upper end extending through an opening 10 in the frame 1. A striker 11 is interposed between the chime bar 3 and the opening 10, and the striker 11 is mounted at the free end of a resilient member 12, here shown in the form of a leaf spring, having its other end secured to the top of the frame 1 at 13. The 45 spring member 12 is offset from the top of the frame 1, so that the striker 11 is normally positioned out of engagement with both the chime bar 3 and the top of the frame 1.

The striker 11 carries washers 14 of non-metallic material, such as felt, which are suitably

secured, as by cement, to the metallic body of the striker 11 that is attached to the spring member 12. Consequently when, in response to energization of the solenoid 7, the plunger 8 moves the striker 11 into engagement with the chime bar 3, there is no metal-to-metal contact between the parts, and the chime bar 3 gives off a clear fundamental note. As previously pointed out, the present invention contemplates means for controlling the tonal characteristics 10 of the sound given off by the chime bar, and a device for this purpose is shown in detail in Figs. 3 and 4.

A lever 15 is pivoted at 16 on a bracket 17, with its free end bearing on the spring member 12 between the striker 11 and the fixed end of the member 12. The lever 15 provides an upwardly extending arm 18 beyond its pivot 16, and a screw 19 threaded into an extension 17a of the bracket 17, bears on the lever arm 18. 20 With the parts in the position of Figs. 1 and 3, the setting of the adjusting screw 19 is such that the lever 15 bears on the spring member 12 with sufficient pressure to impart an initial downward deflection thereto, which tends to bias 25 the striker 11 away from the chime bar 3, and towards the plunger opening 10. Consequently, when the plunger 8 moves upwardly to hit the striker in response to energization of the solenoid 7, the movement of the striker 11 at the end of 30 the spring member 12 is damped, due to the restraining pressure of the lever 15. Therefore, when the striker 11 hits the chime bar 3, the 35 volume and duration of the resulting sound have values determined by the setting of the adjusting screw 19.

When it is desired to decrease the volume, the screw 19 is turned so as to cause the free end of the lever 15 to move downwardly, and thereby increase the initial flexure of the spring member 40 12. Consequently, the member 12 offers more resistance to upward movement of the striker 11 when hit by the plunger 8, and the chime bar 3 is struck a comparatively light blow. Turning 45 the screw 19 in the opposite direction to relieve the initial flexure of the spring member 12 reduces the damping effect, thereby increasing the force of the blow of the striker 11 on the chime bar 3 for a given upward force developed 50 by the plunger 8, with a resulting increase of sound volume. Thus, by manipulating the screw 19, a soft, medium or loud tone can be obtained from the signal. Furthermore, the lever 15 always functions to prevent rebound of the striker 55

11, which might otherwise occur were the spring 12 free to vibrate.

The strength of the blow imparted to the striker 11 by the plunger 8, for a given excitation 5 of the solenoid, is controllable by an adjusting screw 20 at the bottom of the plunger tube 9. The lower end of the plunger 8 rests on the screw 20 when the solenoid 7 is deenergized, and the setting of the screw 20 determines the degree 10 to which the upper end of the plunger 8 extends within the solenoid 7. By means of the screw 20, the length of the plunger stroke, and consequently the force of the blow struck by the plunger 8, can be varied, to thereby obtain an additional control over the volume of sound given off by the chime bar 3 when hit by the striker 11.

The magnetic plunger 8 is surrounded by a thin sleeve 21 of non-magnetic metallic material, such as brass, the function of which is to provide for 20 a certain amount of damping, due to the generation of eddy currents in the sleeve. These eddy currents create a retarding effect on movement of the plunger in the solenoid, and make it necessary for the plunger to become thoroughly saturated, upon energization of the solenoid, before the plunger 8 will move upwardly to hit the striker 11 a single sharp blow, and such retardation of the plunger eliminates any tendency towards premature movement thereof to impart 25 a light blow to the striker 11. Furthermore, the non-magnetic sleeve 21 makes the plunger 8 less liable to rattle in the tube 9 as it moves, due to the reduction of sidewise pull on the plunger by the magnetic frame 1. In other words, the damping 30 of the plunger 8 insures that the plunger will give only a single quick stroke when the solenoid 7 is energized, and that there will be no noise made by movement of the plunger in the tube, to detract from the quality of the tone of the chime bar when hit by the striker 11.

From the foregoing, it is apparent that by the present invention there is provided a signal of the chime type, that is readily controllable as to tonal characteristics and is free from any disturbing influences 45 that might tend to adversely affect the quality of the fundamental note sounded when the signal is operated.

We claim:

1. A device of the class described, comprising 50 a resonant member, a plunger movable toward

said resonant member, a striker interposed between said resonant member and said plunger for cushioning the striking force of the plunger, and means for adjusting the amount of cushioning effect for controlling the tone volume of the fundamental note emitted by said resonant member, when hit by said striker.

2. A device of the class described, comprising a metallic resonant member, a metallic plunger movable toward said resonant member, a striker 10 providing a non-metallic portion interposed between said resonant member and said plunger for cushioning the striking force of the plunger, and adjustable means cooperating with said striker to vary the volume of the sound given off by said 15 resonant member, when hit by said striker.

3. A device of the class described, comprising a metallic resonant member, a metallic plunger movable toward said resonant member, a resiliently mounted striking member providing a non- 20 metallic cushioning portion between said resonant member and said plunger, and adjustable means for setting up a tension in said striking member to determine the tone volume of the sound given off by said resonant member, when hit by said 25 striking member.

4. A device of the class described, comprising a metallic chime bar, a metallic plunger movable toward said chime bar, a resilient member anchored at one end and carrying at its free 30 end a non-metallic cushioning striker interposed between said bar and said plunger, and adjustable means for exerting a pressure on said resilient member intermediate its ends to exert a damping effect on said striker. 35

5. A device of the class described, comprising a metallic chime bar, a metallic plunger movable toward said chime bar, a resilient member anchored at one end and carrying at its free end a non-metallic cushioned striker interposed between said bar and said plunger, a pivotally mounted member having one end bearing on said resilient member, and means for adjusting the degree of pressure exerted on said resilient member by said pivoted member to control the volume and duration of sound given off by said chime bar when hit by said striker. 40 45
